CORE BOX FILLING MACHINE

Thomas N. Fea, Granite City, Ill.

Application November 1, 1948, Serial No. 57,757

4 Claims. (Cl. 22—10)

1

This invention relates generally to machines for filling core boxes used in foundry work, and more particularly to such an apparatus employing compressed air as the ramming or filling medium for the core boxes.

One of the principal objects of this invention is to so construct a mechanism of the kind aforesaid, with a sand-receiving chamber in communication with said core box, and wherein the air blast employed to force the sand in the chamber into the core box will be aided and assisted by a secondary air blast directed at an angle to that of the main blast, to thereby break up any clods or cakes of sand within the said chamber, with the result that free and rapid movement of sand into the core box is obtained.

A second object of my invention is to provide a device of the kind described, wherein there will be two separate blasts for actuating the sand in the chamber into the core box, one of said blasts being the principal mover and directed downwardly through the sand toward the core box, and the other blast being auxiliary and directed substantially transversely through the sand adjacent the lower part of the chamber and releasing it from adherence to the chamber wall and breaking cakes or clods that might have been formed, thereby tending to make holes or openings through the sand adjacent the bottom thereof and accelerating free movement of the sand toward the core box.

Another object of the invention is to construct a machine of the kind described, that may be relatively small in size and cost and that will operate efficiently on a small supply of core sand placed therein, and wherein the frequency of fillings or replacements of sand are at a minimum, inasmuch as there need not be a large head of sand in the sand chamber in order to operate the device efficiently.

A further object of my invention is to provide a core box filler of the kind set forth, employing a sand hopper from which sand is withdrawn from time to time into a sand chamber into which the air blasts are directed, and wherein there will be a valve element for controlling the transfer of sand from the hopper to said chamber and which will also serve as a closure for the chamber to seal the latter to retain the required air pressure therein.

An added object of my invention is to construct a device of the kind hereinbefore mentioned, that will have relief or safety means as part of its pressure sealing member, to vent the sand chamber whenever the air pressure therein is in excess of a predetermined value.

2

The invention has among its other objects the production of a filling machine of the kind described that will be relatively simple and economical in construction and operation, have relatively few parts, and which will be otherwise satisfactory and efficient for use wherever deemed applicable.

Many other objects and advantages of the construction herein shown and described, will be obvious to those skilled in the art to which this invention appertains, as will be apparent from the disclosures herein given.

To this end, my invention consists in the novel arrangement, construction and combination of parts herein shown and described, and the uses mentioned, as will be more clearly pointed out in the following specification.

In the drawings, wherein like reference characters represent like or corresponding parts throughout the views,

Figure 1 is a vertical cross-sectional view, showing the mechanism;

Figure 2 is a side elevation of the same, having the core box and its lift, and the sand hopper, omitted;

Figure 3 is an inside plan view of the chamber door;

Figure 4 is a cross-sectional detail showing the relief vent in the door; and

Figure 5 is a transverse cross-sectional view, taken substantially along the line 5—5 of Fig. 1.

Referring more particularly to the drawings, wherein I have illustrated a preferred embodiment of my invention, there is shown a core filling mechanism useful in foundry operations when making castings.

Although it is not new to use air pressure to force the sand into the core boxes, the machines are very costly, heavy and bulky, bothersome to use, and require much effort on the part of the operator, especially in constantly keeping enough sand in the machine to make a heavy head found necessary in its operation.

To obviate these defects, I have so constructed a machine that will operate on an extremely light head of sand, is of small size, and relatively easy to operate.

1 indicates a platform or table set at any suitable height and having openings 2 and which 50 forms a blower plate through which the core sand is air blasted into a core box 3 placed therebelow. This core box may be of any suitable or preferred size and shape, as may be required from time to time according to the needs of the 55 foundry, and should be vented at 4 through its bottom so as to insure that the sand will be com-

pletely transferred into said box without undesirable air pockets therein.

A sand receiving blower chamber 5 is arranged on said table to extend upright therefrom, with its lower end enlarged relative to its upper end, so as to appear as a truncated member, said lower end sealed against said table, except for openings 2 through the blower plate of the table, so that air or sand in the chamber will be forced downwardly through said openings.

A pipe or conduit 6 leading from a suitable source of compressed air, empties into the chamber through a top opening 1, there being a tank or storage element 8 if desired to build up sufficient volume of air to properly operate the device. A valve 9 is placed somewhere in the line 6 at some point where it will be convenient and easy to operate manually, to thereby control the passage of the air blast from said line, said valve being of any suitable type for the purpose. The pressure in this line should be sufficient to actuate the sand that is in the chamber, downwardly toward the core box that is in place below the blower plate, and although I do not intend this as a limitation, I have found that a line pressure of 100 pounds has been found satisfactory with the core boxes tried in the machine. Of course, the pressure may be made higher or lower as required, or as circumstances warrant.

A sand hopper 10 is arranged to be mounted on said sand chamber or adjacent thereto, in which the supply of core sand is maintained and from whence it may be withdrawn into the sand chamber from time to time as needed, said chamber having an opening 11 through its upright side wall, and said hopper having an open discharge outlet 12 spaced from said opening and in registry therewith.

Obviously a closure is needed to seal the air pressure within the chamber while the sand therein is propelled into the core box, and for this purpose I have arranged a sufficiently strong and durable door 13 pivoted adjacent its circumferential edge at 14, to said side wall of the chamber, and provided with an operating handle 15 for rotating the door about said pivot. This door fits between said opening and discharge outlet to serve as a seal for said chamber as well as a gate valve for the hopper. It is not necessary that the door actually engage the hopper outlet at any time, because the sand in the hopper is slightly moist so as not to be completely free-running, and therefore I have found that a clearance of about $\frac{1}{16}$ " between the door and the hopper is satisfactory, and will be of service in minimizing wear and abrasion therebetween.

In order to seal the door satisfactorily against the air under pressure in the chamber, I have interposed a yieldably compressible gasket element 16 therebetween, as for instance mounted on the door to encircle the chamber opening when the door is closed, this gasket lying partially within a continuous groove or channel on that face of the door opposed to the side wall opening. It is necessary to hold the door against the chamber with sufficient pressure to keep it sealed against the working pressure of the air in the chamber, and to do so I have arranged an operating handle 17 mounted adjacent said door and rotatable relative thereto and provided with one or more locking abutments or cams 18 for progressive engagement with the door after closing of the latter.

As a safety feature and to hold the air pressure in the chamber to a predetermined value, a

vent 19 may be provided at the seal between the sand chamber and door, as by the relatively narrow groove cut in the face of the door that is opposed to the chamber opening and which extends substantially radially from the inner portion of the door to the periphery of the latter beyond said gasket. The gasket will seal said vent under normal conditions, but upon reaching an excess of a predetermined air pressure within the chamber, said air will leak past and under said gasket, travelling in said groove to blow harmlessly into the atmosphere and at an angle that may be made to be away from the usual position of the operator.

It may be desirable that the core box be held firmly in place in set position immediately below the blower plate, and although there may be various mechanisms for accomplishing such a result, I have shown a very simple manner of so doing, as for example by having a vertically movable arm 20 with its upper end carrying a core-box platform 21 thereat and with its lower end pivoted to the end of a pivoted lever 23 carrying an adjustable weight 22 at its other end.

There is great tendency for core sand to form clods and cake and to render the same more readily flowable some form of agitator or vibrator (not shown) may be mounted to shake the sand hopper, and it is also necessary to overcome this caking tendency in the blower chamber too. Otherwise, an exceptionally great pressure head must be maintained in the chamber, causing much trouble in maintaining the high sand level in the same, but also needing a much larger mechanism for the purpose.

I have found, however, that if an auxiliary blast of air is directed through the lower body of sand within the chamber, substantially laterally or transversely, the cakes or clods are broken up and causes openings to be formed in the sand adjacent the chamber bottom, thus accelerating the travel of the sand downwardly into the core box.

This auxiliary line is indicated at 24, controlled by a suitable, manually controlled valve 25, and is arranged in any desired manner, as by a regulator or other means (not shown) or by the reduced diameter of the pipe as compared with that of the air line 6, so that the pressure discharged therefrom is less than that through the main pipe 6. A conduit 26 is arranged to lie within the lower portion of the chamber and extend about the interior periphery of the latter, and is provided with jets or orifices 27 directed to discharge air relatively transversely or laterally of the chamber bottom or across the same. These jets may be further made more efficient by staggering their axes so that they shoot the air at varying angles, although in a generally transverse direction.

When the air is blasted through such an auxiliary member, not only are the cakes and clods broken up in the bottom of the sand within said chamber, but there is a tendency to make pockets in that portion of the sand, and thereby accelerate the movement of the sand from above toward the core boxes.

In operation, and assuming that the core box is in proper position below the blower plate of the chamber, and that the closure door has been closed tightly, the valves from the main line and the auxiliary line are opened one or more times, depending upon the size of the core openings at the time, and thus the main air blast will be directed downwardly through the body of sand within the chamber to actuate said sand toward

the core box, while the auxiliary air blast shoots across the bottom of the chamber through said sand, breaking up any cakes therein, and permitting the sand to fill the core box. As soon as the core box is filled, the pressure within the chamber will exceed the predetermined value originally set, and the excess will vent through the safety vent in the door of the machine. The core box may then be replaced by another, and the same operations gone through again. From time to time, the door must be temporarily opened to permit sand to flow into the chamber from the hopper, and the door is then re-closed to normal operative position.

Having thus described my invention, it is obvious that various immaterial modifications may be made in the same without departing from the spirit of my invention; hence I do not wish to be understood as limiting myself to the exact form, arrangement, construction and combination of parts herein shown and described, nor uses mentioned, except as limited by the state of the art to which this invention relates, and by the claims hereunto appended.

What I claim as new and desire to secure by Letters Patent is:

1. The combination with a source of compressed air and a core box, of a chamber opening into and arranged intermediate the two and communicating with said box at its lower end, a sand hopper mounted adjacent said chamber and opening into the latter for controlling passage of sand through said opening into said chamber, conduit means communicating with said source of compressed air and the upper end of said chamber for admitting the air to blast downwardly onto the sand in said chamber, and additional conduit means communicating with said source of compressed air and the lower part only of said chamber for directing an air blast substantially transversely through only the lower portion of the body of sand in said chamber.

2. The combination with a source of compressed air and a core box, of an upright air pressure chamber therebetween and communicating with the same, of a sand hopper adjacent said chamber and emptying into the latter, means for controlling the flow of sand from said hopper into said chamber, conduit means for communication between said source of compressed air and the upper portion of said chamber for admitting said air downwardly into the chamber to force the sand therein toward said box, and separate conduit means communicating between said source of compressed air and the lower portion only of said chamber to admit an air blast substantially transversely across the lower portion only of said chamber to blow the sand inwardly of the upright enclosing wall of said chamber with sufficient force to break up the lumps of sand therein.

3. The combination with a source of compressed air and a core box, of an air pressure chamber

opening onto and arranged intermediate said box and source and communicating with said core box therebelow, conduit means between said source of compressed air and the top of said chamber, a sand hopper, means between said hopper and chamber for controlling the passage from said hopper to said chamber, a valve controlling passage of said compressed air through said conduit means and admitting said air downwardly through said chamber, an air duct between said source of compressed air and said chamber and extending substantially about the inner periphery of the latter and having outlets directed substantially transversely across the lower portion only of said chamber, and a valve in said last-mentioned duct and controlling admission of said air into said duct to discharge the same through said outlets only and force said sand inwardly thereof toward the center of said chamber.

4. The combination with a source of compressed air and a core box, of a sand hopper having a discharge outlet, a chamber member communicating with said source of air supply and arranged intermediate said source of air supply and said box and communicating adjacent its lower end with the latter, said chamber having a side opening in registry with and spaced from said discharge outlet, a door member insertibly movable into place between said opening and said outlet to control passage of sand therebetween, a resilient endless gasket between said door member and chamber member, means for forcing said door toward said chamber to compress said gasket substantially uniformly throughout its length and form an air seal for said chamber member, and a relief vent groove transversely across one of said last-mentioned cooperating members beneath said gasket so that said gasket is less tightly compressed at said groove than elsewhere of its length and whereby the gasket will be unsealed at said groove before at any other portion whenever the air pressure within said chamber exceeds a predetermined amount.
